(57) **CLAIM**

The ornamental design for the fishing tackle box, as shown and described.

DESCRIPTION

FIG. 1 is a perspective view of the fishing tackle box; FIG. 2 is an exploded view of a first embodiment of the fishing tackle box showing a centre spindle inside the mid portion;

FIG. 3 is an exploded view of a second embodiment of the fishing tackle box, with the centre spindle removed and all other views being the same;

FIG. 4 is a side elevational view of the fishing tackle box; and,

FIG. 5 is a top plan view.
